CLAIM

The ornamental design for a flag holder, as shown.

DESCRIPTION

FIG. 1 is a top perspective view of a flag holder, showing my new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a right side elevation view thereof, showing additional example environmental structure.

The broken lines showing an example flag pole and flag, as well as the back side mounting surface in FIG. 3, illustrate example environmental structure, are not part of the design sought to be patented, and form no part of the claimed design.
